UNITED STATES PATENT OFFICE.

TOM L. JOHNSON, OF CLEVELAND, OHIO.

CABLE-WAY FOR RAILWAY TRACTION-CABLES.

SPECIFICATION forming part of Letters Patent No. 310,284, dated January 6, 1885.

Application filed July 22, 1884. (No model.)

To all whom it may concern:

Be it known that I, Tom L. JOHNSON, of Cleveland, in the county of Cuyahoga and State of Ohio, have invented a new and useful 5 Cable-Way for Railway Traction-Cables, which invention or improvement is fully set forth and illustrated in the following specification and accompanying drawings.

The object of this invention is to provide a 10 permanent way for cable railways of small area of cross-section, of very strong and durable construction, and of as little obstruction as possible to street travel or traffic. The 15 means of attaining these ends and the advantages thereby secured are hereinafter described and explained.

The novel features of which the invention consists are specifically set forth in the claims.

In the accompanying drawings, Figure 1 is 20 a side view of two of the slot-rails forming one side of the cable-way, showing plate-connection at joint of rails, and a transverse section of a metal cross-tie below said joint, upon which the said rails are secured. Fig. 2 is a 25 transverse section through the lower portions of two slot-rails forming opposite sides of the cable-way, and a similar section through a plate forming a bottom for said cable-way. Fig. 3 is a general view showing a cross-tie 30 in longitudinal elevation, with the slot-rails, forming the cable-way, in transverse section, secured to said cross-tie, and also a transverse section of one rail of the car-track secured to said cross-tie, said rail and cable-way being 35 tied together by a brace or rod running transversely thereto. Fig. 4 shows, partly in section, a method of securing the slot-rails forming the cable-way to a lower chair and wooden cross-tie, said chair taking the place of the 40 metal cross-tie shown in preceding figures, and being spiked to the wooden cross-tie illustrated in said figure. Fig. 5 shows the slot-rails in transverse section, rolled to the same bevel or angle shown in preceding figures, but 45 devoid of lower flanges, and the method of securing said rails to the metal cross-tie. Fig. 6 shows the slot-rails in transverse section, and provided with square legs or feet. Fig. 7 shows the slot-rails in similar section, provided with double-beveled legs or feet.

In said figures, now to be more particularly described, the several parts are respectively designated by letters as follows:

In the several figures, the letters A A indicate two slot-rails, forming the sides of the 55 cable-way. B indicates a metal cross-tie; C, the bottom proper of the cable-way, composed of a series of plates or of composition, completely filling the spaces between and covering 60 said cross-ties up to a line above the same, except at certain points, at which points metal chocks F are introduced and either riveted or bolted to the cross-ties, as shown in Figs. 1 and 7. In Fig. 1 said chock is shown at the joint of the two slot-rails A A, at which joint 65 the rivet-holes or bolt-holes in the fish-plate a are slotted, as shown at b in dotted lines, to provide for expansion and contraction in the surrounding metal parts.

In Fig. 2 a plate, C, is illustrated in transverse section, showing the slot-rails A A resting upon its exterior rabbets, c' c', and its interior surface, c'', projecting up within the cable-way sufficiently to cover the level of the cross-ties flush with the upper surfaces of the chocks 75 F, resting upon said ties. The plate C may be made of any suitable material, and if partially elastic, as iron, or even earthenware, the tamping of the surrounding road-bed will bring them to a fairly even bearing along their 80 length, and their shape is such, as shown in Fig. 2, that no pressure can force them upward against the resistance of the side rails upon their rabbets c' c'. The chocks F and plates C thus forming a continuous bottom 85 surface for the cable-way, flush and smooth, the whole interior of said cable-way presents a clean contour, devoid of any obstructions or receptacles for the collection and accumulation of dirt. The plates C are prevented 90 from any end movement by their joints tightly abutting the chocks F.

In Fig. 3 is illustrated the general construction of the cable railway as the same would appear beneath the surface of the road-bed, 95 with one side of the car-track omitted, and the slot-rails and one car-rail in transverse section. In said figure the letter D indicates a girder car-rail, secured in a chair, E, bolted, as shown in said figure, to the metal cross-tie 100

B. Said chair may be riveted instead of bolted to the cross-tie B, if preferred, or, of course, may be spiked to a wooden cross-tie, if desired. The slot-rails A A, hereinbefore described, are secured to the cross-tie B by the foot-braces G, overlapping their lower flanges, and the feet of said rails are firmly spread and held under said braces by the chocks F. The braces G are bolted, as shown in said figure, to the cross-ties B, but may be riveted thereto, if preferred. The braces C', which may be rods secured by screw-threads and nuts at their extremities, are preferably made of flat metal bars placed on edge, as shown, and riveted through flanges on their ends to the webs of the rails D of the track, and to the slot-rails A A by rivets r on each side of the cable-way. Said braces can thus be readily worked in between the paving sets or street-paving of whatever construction, and be attached, as shown, very near the head of the slot-rails A A. Such points of attachment it is very desirable to secure in order to most effectually keep said rails in place. Said braces C', it will be further observed, act effectively, both in tension and compression. They should preferably be placed every three feet apart and the cross-ties B every six or eight feet apart.

In Fig. 4 is illustrated the same cable-way, with the slot-rails A A in transverse section, but secured to a cast-metal chair, L, adapted to support said rails on a wooden cross-tie, M, to which said chair is spiked by the spikes l l'. The chair L is thus practically substituted for the metal cross-tie B shown in preceding figures. It also, by its chock l projecting into the cable-way, fulfills the office of the chock F shown in the other figures. The foot-braces G, abutting the lugs l' on the chair L, perform the same office as that described for them in preceding figures.

In Fig. 5 the slot-rails A A are shown in transverse section devoid of lower angles, the angle-braces H and the chock F securely fastening said rails by means of rivets to the cross-tie B.

In Fig. 6 the slot-rails A A are shown in transverse section, with small lower flanges and foot-braces J, and chock F, modified to fit the shape of said flanges.

In Fig. 7 the slot-rails A A are shown in transverse section, with double-beveled feet and foot-braces K, and chock F, modified to fit the shape of said feet. Said chock and braces are shown in said figure bolted to the cross-tie B by bolts f', instead of by rivets, as shown at f in the other figures; but rivets may be substituted for the bolts f', if preferred.

Among the advantages of the constructions above described, compared generally with cable-railway "tunnels" as ordinarily constructed, may be stated the following: In ordinary practice on cable railways a "grip" of comparatively large size is used, which grip of necessity must travel in the same passage-way

provided for the cable. This fact has necessitated large passage-ways generally, and very properly termed "tunnels." In another application for Letters Patent made by me, filed on the 29th day of April, 1884, and now pending, bearing the Serial No. 129,701, I have described a new method of cable construction, wherein the connection between the car and cable is effected by means of a notched rotary disk or wheel instead of by a grip. So little of the said disk enters through the slot in the cable passage-way that its presence need not be considered in the construction of said way, whereas when the large grip is used the size of the passage-way must be determined by that of such large grip; hence said way is in practice so large that it is properly described as a "tunnel." By dispensing with the grip, therefore, the passage-way can be constructed solely with a view to the proper passage of the cable, and in such practice said way becomes so much smaller that it in no sense can be appropriately called a "tunnel" either in appearance or name. It is most appropriately termed a "cable-way" instead of a tunnel, and is so designated in my said application.

The cable-way herein described and claimed is of smooth interior surface, of small transverse area, and composed only of two side rails and a bottom, its bottom being made of cement, concrete, or of any solid and compact material, or of plates, if preferred, of any suitable material, but preferably of the earthenware of which sewer-pipes are made.

In the construction of ordinary tunnels of cable railways, yokes are used to tie the system together, the track included, every four or five feet apart. The tunnel is then built of brick, concrete, or iron plates about or around said yokes (which form a skeleton frame therefore) throughout its whole length, the inner surfaces of said yokes generally being flush or coinciding with the interior surface of the tunnel. Said yokes are sometimes made of cast-iron and sometimes of wrought-iron, and whenever used the shape of the slot-rails above the tunnel is largely determined by its connection to said yokes, for which connection it requires a flange to be rolled on its lower surface. This flange acts at the same time as a projection to receive the covering-plates often used in tunnel construction, and also as a flange to which the ends of the iron plates may be riveted, if such are used in building the walls of the tunnel. The use of this lower flange is attended with material difficulties and disadvantages.

First. The difficulty of rolling or shaping said flange is an element of great cost.

Second. When this flange is used as the means of connection to the rest of the system, it must be drilled at such places as the yokes or ties are set. This necessitates the use of a slot-rail of uniform length drilled to a uniform gauge or distance of holes apart, or, as an alternative, the placing of the yokes at odd distances

apart when the slot-rails are not of uniform length, which in effect requires the yokes, as they cannot be farther apart than the standard distance, to be put closer together than such standard distance; hence additional cost in this item, for the yokes should be placed under the joints of the slot-rails when the lower flanges of said rails are depended upon for connection with the rest of the system.

10 Third. The greater nicety of construction required necessitates additional cost.

Fourth. Where connection with the yoke by means of lower flanges on the slot-rails is depended upon, great waste of material in construction must ensue, for the yoke serving the double purpose of supporting the track and the slot-rails also, the track, if a stringer-track, does not need the yokes to be closer together than four feet, and with a girder-rail track the 20 yokes need be not closer than seven or eight feet, whereas the slot-rails should be supported laterally at less distances than these mentioned, for said rails should be held in place to great nicety. A variation of one-fourth or even one-half inch, which would not seriously affect the rails of the track, would be fatal to the use of the slot-rails, which are but from three-fourths of an inch to one inch apart in the slot, and in 30 practice great difficulty has been found in maintaining said rails in accurate line of adjustment; hence it is a mistake to depend upon the yokes and lower flanges on the slot-rails as means of supporting the slot-rails in place laterally, when the track-rails only need 35 said yokes at distances apart much greater than are absolutely required by the slot-rails to preserve their necessary alignment.

All the above-mentioned difficulties and disadvantages of construction are obviated by my 40 invention hereinbefore described, as will appear by the following summary of the advantages flowing from the constructions constituting said invention: First, the lower flanges of the slot-rails are dispensed with, lightening 45 the whole structure, both yokes and the tunnel proper being entirely dispensed with also; second, the slot-rails, being fished by side plates at their ends or joints, may be made of any lengths, and, no uniformity in length being required, no drilling at uniform distances for connection to any yokes is required; third, increased speed and economy in laying the plant or system, particularly when the closing 50 of the cable-way by bottom plates is considered; fourth, the interior of the cable-way pre-

sents a smooth contour clear of obstructions, for the collection and accumulation of dirt, rendering it an easy matter to dispose of any dirt that may enter the cable-way, by either sweeping or drainage, or both; fifth, the non- 6c obstruction of street traffic or travel due to the small space occupied by the slot-rails at the surface of the street. The bevel given to said rails in rolling, allowing the cable-way to taper to the top, as shown in the drawings, 65 thus exposes a minimum of rail-surface to the possibility and even great danger of causing horses to slip and fall in passing over such rails, as frequently happens upon slot-rails as ordinarily laid in cable-ways now in practical 70 operation.

I am aware that a beveled rail *per se* is not new, nor in combination with a cable-railway tunnel, and such I do not claim; but,

Having thus fully described my said cable-way and its mode of construction, as of my invention I claim—

1. In a cable-railway system, a cable-way composed of bevel-rolled slot-rails on each side, with or without lower angles or feet, and 80 provided with a bottom at the base of said rails, substantially as and for the purposes set forth.

2. In a cable-railway system, a slotted cable-way composed of rails on each side, butt-jointed or fished by outside plates or bars, as 85 *a*, and secured by inside chocks, substantially as and for the purposes set forth.

3. In a cable-railway system, in combination with the rails of the track, a slotted cable-way 90 tied on each side directly to said rails by rods or braces, as *C'*, substantially as and for the purposes set forth.

4. In a cable-railway system, in combination with a cable-way composed of slot-rails, as *A* 95 *A*, the inside chocks, outside foot or angle braces, and cross-ties for supporting said cable-way, substantially as and for the purposes set forth.

5. In a cable-railway system, in combination 100 with the rails of the track, a slotted cable-way composed of slot-rails, as *A A*, rods or braces, as *C'*, inside chocks, outside foot-braces, and cross-ties for supporting said cable-ways, substantially as and for the purposes set forth.

TOM L. JOHNSON.
